UNITED STATES PATENT OFFICE

2,550,303

DISPENSING HOPPER FOR DISTRIBUTING MACHINES

Tom B. Simpson, McAllen, Tex.

Application October 1, 1946, Serial No. 700,570

3 Claims. (Cl. 222—176)

1

My invention relates to a machine for spreading fertilizer, seed, or other small aggregates.

An important object of the invention is to provide simple and reliable adjustable means for supplying the material to the rotatable spreader disc.

A further object of the invention is to provide means for pivotally mounting the valve element upon the lower end of the hopper so that it may be turned and for locking the same in the selected adjusted position.

A further object of the invention is to provide means whereby the spreader disc may be rapidly rotated from the traction wheel of the machine.

Other objects and advantages of the invention will be apparent during the course of the following description.

In the accompanying drawings, forming a part of this application and in which like numerals are employed to designate like parts throughout the same,

Figure 1 is a side elevation of a machine embodying my invention.

Figure 2 is a front end elevation of the same.

Figure 3 is a plan view of the machine.

Figure 4 is a central vertical longitudinal section through the hopper and associated elements, parts broken away.

Figure 5 is a central vertical section through a gear housing, the gears being shown in elevation, and,

Figure 6 is an enlarged side elevation of a U-shaped bracket and associated elements, parts omitted.

In the drawings, wherein for the purposes of illustration is shown a preferred embodiment of my invention, the numeral 10 designates a frame, including radius rods 11, which converge forwardly and are rigidly connected with upper and lower plates 12, forming a hitch. These plates have openings 13. The numeral 14 designates axle housings, rotatably holding axles 15 and 16, having traction wheels 17 and 18 rigidly secured thereto. At their inner ends, the axle housings are rigidly connected with a gear housing 19, including a vertical cap 20.

Mounted above the frame 10 is a vertical truncated conical hopper 21, which tapers downwardly and has a closed bottom 22. This hopper is supported by bars 23 and 24, rigidly attached to the top of the hopper. The bars 23 are rigidly secured to the axle housings 14, while the bars 24 are rigidly secured to the radius rods 11.

Slidably mounted upon the lower end of the hopper 21 is a downwardly tapering truncated

2

sleeve valve 25, having a closed bottom 26. At its top, the valve 25 is provided with an outwardly projecting annular flange slideably engaging above a ring 27. This ring has ears 28 rigidly secured thereto, and these ears have rods 29 rigidly secured thereto. The rods 29 are slideably mounted within openings formed in stationary brackets 30, rigidly attached to the hopper 21. The upper ends of these rods are threaded for receiving nuts 31, and compressible coil springs 32 are arranged between the nuts and brackets, as shown. It is thus seen that the valve 25 is yieldingly supported in engagement with the lower end of the hopper, but may turn thereon.

15 A radial handle 33 is rigidly secured to the valve 25 to turn it. A depending U-shaped bracket 34 is provided rigidly attached to the ring 27. This bracket has a bottom strip 35 having an elongated slot 36. This bottom strip may be longitudinally curved to be concentric with the valve 25. A bolt 37 is rigidly attached to the valve 25 and is radial and extends through the slot 36 and carries a winged nut 37'. By adjusting this nut 37' it will be brought into clamping engagement with the strip 35 and lock the valve in the selected adjusted position. The valve is provided adjacent to its bottom with an opening 38, to be brought into and out of registration with an opening 39 formed in the hopper 21, adjacent to its bottom.

20 Arranged beneath the truncated sleeve valve 25 and concentric therewith is a horizontal rotary spreader disc 40, the upper face of which is concave and provided with radial ribs 41. This spreader disc is rigidly mounted upon a vertical spindle 42. Arranged within the lower portion of the hopper 21 is an upper rotary feed disc 43, the upon face of which is horizontal and flat. This feed disc is concentric with the hopper 21 and spaced a short distance from the side of the hopper, as shown. The feed disc 43 has a sleeve 44 rigidly secured thereto and concentric therewith, and this feed disc has a coupling tongue 45, rigidly secured thereto and arranged within the sleeve 44. The sleeve 44 receives the upper end of the spindle 42, which has a radial groove 46 to receive the tongue 45, so that the disc 43 rotates with the spindle. Rigidly secured to the sleeve 44 are radial agitators 47, operating within the hopper 21 near its bottom and near the outlet openings.

25 The spindle 42 extends into the cap 20 of the gear housing, and passes through an end thrust bearing 47. The spindle 42 is provided with a small bevel gear 48, rigidly secured thereto, en-

gaging a large bevel gear 49, rigidly mounted upon the axle 16.

The operation of the machine is as follows:

The machine may be attached to a tractor or the like so that the frame 10 will be held horizontal and travel with the tractor. The rotation of the traction wheel 18 is transmitted to the vertical spindle at an increased speed. The rotating feed disc will cause the material to be thrown outwardly by centrifugal force so that such material will be supplied in a regulated amount to the bottom of the hopper. This material at the bottom of the hopper is acted upon by the agitators and will discharge through the openings 38 and 39 and be deposited upon the inner portion of the spreader disc. This material is thrown outwardly by the spreader disc due to the action of centrifugal force.

It is to be understood that the form of my invention herewith shown and described is to be taken as a preferred example of the same, and that various changes in shape, size and arrangement of parts may be resorted to without departing from the spirit of my invention or the scope of the subjoined claims.

Having thus described my invention, what I claim is:

1. A machine for spreading finely divided material, comprising a wheeled frame, a conically tapered truncated hopper mounted upon the wheeled frame and provided near its bottom end with a side discharge opening, a conically tapered truncated valve closed at the bottom and slidably engaging over the bottom end of the hopper and having a side opening for registry with the side opening of the hopper, an annular radial flange secured to the top end of the valve, an annular ring disposed beneath the radial flange for supporting the valve, ears secured to the ring, rods connected with the ears and extending above the same, bracket means connecting the rods and hopper for supporting the rods, a member mounted upon the ring, and an adjustable device secured to the valve and engaging the member to lock the valve against turning.

2. A machine for spreading finely divided material, comprising a wheeled frame, a conically tapered truncated hopper mounted upon the wheeled frame and provided near its bottom end with a side discharge opening, a conically tapered truncated valve closed at the bottom and slidably engaging over the bottom end of the hopper and having a side opening for registry with the side

opening of the hopper, an annular radial flange secured to the top end of the valve, an annular ring disposed beneath the flange for supporting the valve, mechanical means connecting the ring with the side of the hopper for supporting the ring and holding it against turning, a depending U-shaped bracket secured to the ring and spaced from the valve and having a longitudinal slot, and a substantially radial bolt carried by the valve and engaging in the slot and receiving a nut to clamp the valve against turning.

3. A machine for spreading finely divided material, comprising a wheeled frame, a concically tapered truncated hopper mounted upon the wheeled frame and provided near its bottom end with a side discharge opening, a conically tapered truncated valve closed at the bottom and slidably engaging over the bottom end of the hopper and having a side opening for registry with the side opening of the hopper, an annular radial flange secured to the top end of the valve, an annular ring disposed beneath the radial flange for supporting the valve, apertured ears secured to the ring, generally vertical rods engaging in the apertures of the ears and extending above the same, L-shaped brackets secured to the hopper and having openings to receive the rods, nuts carried by the top ends of the rods, coil springs surrounding the rods between the L-shaped brackets and nuts to resiliently support the valve, a member mounted upon the ring, and an adjustable device secured to the valve and engaging the member to lock the valve against turning.

TOM B. SIMPSON.
